UNITED STATES PATENT OFFICE

JOSEPH SICILIANI, OF CHICAGO, ILLINOIS

DESIGN FOR A CONTAINER FOR PASTRY OR THE LIKE

Application filed March 6, 1930. Serial No. 34,756. Term of patent 14 years.

To all whom it may concern:

Be it known that I, JOSEPH SICILIANI, a subject of the King of Italy, residing at Chicago, county of Cook, and State of Illinois, have invented a new, original, and ornamental Design for a Container for Pastry or the like, of which the following is the specification, reference being had to the accompanying drawings, forming part thereof, wherein—

Fig. 1 is a side view of the dish.

Fig. 2 is a bottom view of the dish.

Fig. 3 is a sectional view taken on line 3—3 of Fig. 2.

I claim:

The ornamental design for a container for pastry or the like, as shown.

JOSEPH SICILIANI.
